DESIGN FOR A TOY BOAT

August Rietzke, Gordons Corners, N. J.

Application March 1, 1945, Serial No. 118,199

Term of patent 14 years

(Cl. D34—15)

To all whom it may concern:

Be it known that I, August Rietzke, a citizen of the United States, residing at Gordons Corners, in the county of Monmouth and State of New Jersey, have invented a new, original, and ornamental Design for a Toy Boat, of which the following is a specification, reference being had to the accompanying drawing, forming part thereof.

I claim:

The ornamental design for a toy boat, substantially as shown.

AUGUST RIETZKE.
